UNITED STATES PATENT OFFICE.

MATTHEW JOHN CROCKER, OF HELENA, ARKANSAS, ASSIGNOR OF ONE-HALF TO BERT C. POUNCEY, OF MEMPHIS, TENNESSEE.

COTTON-GIN CONDENSER.

1,320,379.

Specification of Letters Patent.

Patented Nov. 4, 1919.

Application filed June 23, 1919. Serial No. 306,161.

To all whom it may concern:

Be it known that I, MATTHEW J. CROCKER, a citizen of England, and a resident of Helena, in the county of Phillips and State 5 of Arkansas, have made certain new and useful Improvements in Cotton-Gin Condensers, of which the following is a specification.

My invention relates to cotton condensers, 10 and has reference more particularly to condensers used in connection with cotton gins.

An object of the invention is to provide means for condensing cotton after leaving the gin.

Another object is to provide a condenser 15 that will also prevent the passage of dust and dirt along with the condensed cotton.

Another object is to provide means for 20 separating dirt, dust and foreign matters from cotton after leaving the gin.

With these and other objects in view my invention consists in certain novel features of construction, arrangement and combination of parts, as will be hereinafter fully 25 described and pointed out in the claims, reference being had to the accompanying drawings, in which:

Figure 1 is a transverse vertical section through the device;

Fig. 2 is a longitudinal vertical section 30 of same;

Fig. 3 is an enlarged side elevation of a gear wheel driving the condensing cylinder;

Fig. 4 is a plan view of the baffle or deflector support.

In the drawings which show a practical embodiment of my improvement I propose to use a supporting frame composed of uprights 10 connected by upper cross beams 40 11 and lower cross beams 12. Mounted on the top of the frame on the cross bars 12 is a rigid shaft having alined end portions 13 and the intermediate offset or cranked portion 14, the end portion rigidly held to 45 the top of the frame.

Upon the end portions 13, 13 of shaft are rotatably mounted the hubs 15 of the cylinder heads 16 upon which heads are held the tubular cylinder 17 or wire screen which 50 constitutes the condensing cylinder.

Fitted on the hubs 15 of the tubular screen are the end walls 18 of the casing or housing of the condenser, the top or hood 19 extending over the condensing cylinder 17 and 55 the side walls 20 extending downwardly

and inwardly forming a chute or flue 21 through which the dust and other debris that flows through the wire screen may pass.

Through one side (the side nearest the gin) an opening of suitable extent is made 60 and in this is inserted the flue spout 22 leading from the gin, said flue being somewhat upwardly inclined and extending very close to the periphery of the screen 17, at its upper portion. In the opposite wall of 65 the casing, but adjacent the lower part of the periphery of the cylinder are disposed the doffing rolls 23, and above said rolls in the wall is introduced a slab 24.

Within the tubular screen 17 is mounted 70 a stationary baffle or deflector which comprises a sheet metal plate, designated generally at 24, said plate being of such length as to nearly fill the interior of the cylinder 17 longitudinally, leaving just sufficient 75 space to permit the cylinder heads to rotate, as the baffle remains stationary. The width of baffle or deflector 24 is such as to nearly fill the cylinder transversely, leaving sufficient space to permit the revolution of the 80 cylinder around such baffle.

The baffle or deflector is of a peculiar shape being struck on a compound or ogee shape, the upper concave portion 25 facing and extending toward the inlet flue from 85 the gin, while the lower portion 26 faces toward the doffing rolls 23, the curvatures of 25 and 26 being such that if continued that of 25 would approximate the end of flue and that of 26 would approximate the 90 lower periphery of the lower doffing roll 23.

By this construction and arrangement of the baffle, little or no air reaches the circumference of the screen cylinder 17 between the points *x* and *y*, so that the condensed cotton on the face of the cylinder 95 will be readily pulled off by the doffing rolls.

The baffle or deflector is rigidly secured to the offset or cranked portion 14 of the rigid shaft, this portion 14 being rectangular in cross section, by bent metallic braces 27 which are secured at about their centers to inner side of the crank arms 14^a by bolts or webs and at their ends to angle iron ribs 28 rigidly secured to the ogee curve baffle, 100 said ribs conforming in shape to the shape of the baffle or deflector and the braces 28 holding the same at the proper angle to flue from the gin.

A sprocket gear 29 having a hub 30 is 110

mounted on hub 15 of the cylinder and is rigidly connected therewith by being bolted or otherwise.

While it has been stated that the baffle board or deflector may be made of sheet metal, it is of course obvious that any other suitable material may be used for this purpose, and the deflector may be placed at any angle to best deflect the current of air which carries dust and debris, downward through the flue, a current being created in that direction either by suction or otherwise.

It will be noted that by offsetting the shaft carrying the deflector a greater unobstructed space is provided for the effect of the down draft of air on the dust and dirt, and hence practically all of the dust and dirt will be pulled out as it were from the cotton after leaving the gin.

20 The operation of the device is as follows:

The cotton passes through the gin (not shown) at the left of flue and the saws at the gin pull the lint from the seed and the brush of the gin takes the lint from the saws and creates a draft which drives the cotton through the flue and against the rotary wire screen 17. This screen catches and holds the cotton lint, but the dust, dirt and other debris passes through the screen and strikes against the deflector 24, and drops down through the discharge or flue 21, the offsetting of the deflector and its angular arrangement relative to the intake of air adding greatly to the effectiveness of the device in accomplishing its stated purposes.

It should be noted that the concave portion 25 of the deflector presented to the flue 22 is of greater extent than convex portion at this side, hence a flared out or fan shaped area will be produced through which the draft will act on the dust or dirt.

I claim:

1. The device as herein characterized and comprising a casing, having a combined air and lint inlet, an air outlet and lint outlet, a tubular reticulated screen mounted for rotation within said casing and interposed

between said inlets and outlets, and a stationary baffle comprising a plate obliquely disposed within said tubular screen. 50

2. A device as herein characterized and comprising a casing having a combined air and lint inlet, an air and dust outlet, and a lint outlet, a tubular screen mounted for rotation within the casing and between said inlets and outlets, and a stationary baffle plate within said screen, said baffle comprising a plate disposed obliquely across nearly the breadth of the screen and within the same, and away from said air and lint inlet. 60

3. A device as herein characterized consisting of a casing having combined air and lint inlets, and air and cotton lint outlets, a tubular screen mounted for rotation within said casing, and a stationary baffle plate 65 or deflector mounted within said screen, said deflector having reversely curved portions opposing the combined air and cotton inlet of the casing.

4. A device as herein characterized and comprising a casing having a combined air and cotton inlet and air and cotton outlets, a tubular condensing screen mounted to rotate in said casing and in the path of said air and cotton inlet, and a deflector plate 75 stationarily mounted within said screen, said deflector consisting of an ogee curve and offset from the axis of the screen.

5. A cotton gin condenser comprising a combination, a supporting frame, a cranked 80 shaft rigidly mounted on said frame, a tubular reticulated condensing cylinder rotatably mounted on said rigidly mounted cranked shaft, a casing within which said cylinder rotates, said casing having lateral 85 inlets and outlets disposed in opposite sides and a draft flue at its lower end, an ogee curved deflector plate within said condensing cylinder and rigidly secured to the cranked portion of the aforesaid shaft, and 90 means for rotating said condensing cylinder.

MATTHEW JOHN CROCKER.
